UNITED STATES PATENT OFFICE

2,492,138

MECHANICAL MODULATOR FOR RADIO BEACONS UTILIZING TWO TONES

Charles William Earp, London, England, assignor, by mesne assignments, to International Standard Electric Corporation, New York, N. Y., a corporation of Delaware

Application December 12, 1944, Serial No. 567,835
In Great Britain February 23, 1940

Section 1, Public Law 690, August 8, 1946
Patent expires February 23, 1960

12 Claims. (Cl. 332—56)

1

The present invention relates to modulators for the production of a single or double side band corresponding to the modulation product of a high (carrier) frequency modulated by a low frequency, and is particularly though not solely suitable for application to radio beacons using two tones for blind landing systems.

In modern radio beacon systems, and in particular radio landing systems for aircraft, it is necessary to "identify" different radiations with different modulations. Such modulating arrangements are preferably mechanical, as a very high degree of "balance" between the several radiations is necessary, this condition making valve modulating systems unsatisfactory.

In some of these systems, it is desirable to radiate no carrier wave, or to radiate a single sideband from a particular aerial. In particular, in systems for radio landing where off-set radiation patterns are used, it is most advantageous to radiate no carrier wave, and still better to radiate single sideband from at least one aerial.

It is the object of the present invention to provide arrangements whereby double sidebands without carrier, or single sideband may be produced by mechanical modulation. The stability of mechanical modulation devices depends solely upon mechanical accuracy.

A particular advantage of the mechanical modulators constructed according to this invention is that they are specially suitable for modulation of very high frequencies, where filtering methods are not practical.

A valuable application for the single sideband producer may be found in radio telegraph systems, where it is desired to radiate a multi-channel single sideband system, or to key marker and spacer waves on slightly different frequencies.

According to the broad aspect of the invention a modulator for the production of a single or double sideband corresponding to the modulation product of a high (carrier) frequency modulated by a low frequency, comprises two mechanical parts electrically associated with each other so that the electrical condition of one is dependent upon the electrical condition of the other which is excited by electrical energy of the said high frequency, said two parts being also relatively movable with respect to each other at a relative speed such that the frequency of the cycle of variations of the electrical conditions of said one part differs from the said high frequency by the said low frequency.

According to another aspect of the invention

2

a balanced modulator for the production of two frequencies corresponding to the sidebands resulting from modulation of a high frequency wave by a low frequency is characterised in that the modulation is effected by the rotation of one or more mechanical parts.

According to another aspect of the invention, a modulator for the production of a single frequency sideband corresponding to one of the bands resulting from the modulation of a high frequency by a low frequency is characterised in that the modulation is effected by the rotation of one or more mechanical parts.

The invention will be better understood from the following description of the principle of operation and several embodiments thereof illustrated in the accompanying drawings in which:

Figs. 1a and 1b show arrangements for obtaining simultaneously two sidebands;

20 Figs. 2a and 2b show arrangements for obtaining a single sideband;

Figs. 3a and 3b show a modified arrangement of Fig. 2b incorporated in an unsymmetrical and a symmetrical system respectively;

25 Fig. 4 shows a modified arrangement of Fig. 3a for the case when the wavelength of the high frequency is rather large to meet practical applications of the invention; and

Fig. 5 shows an arrangement adapted for use 30 with polyphase supply of high frequency.

The principle of operation of the devices according to the invention is the rotation of a collector in a "radiogoniometer." In Fig. 1a, a fixed coil F having two parts symmetrically located on opposite sides of a diameter is fed with radio frequency f_1 , and a coil S located between the two parts of F rotates at frequency f_2 in the field of F. The output from the rotating coil S contains frequencies (f_1+f_2) and (f_1-f_2) , but not f_1 or f_2 . If the coupling between the two coils F, S is proportional to the cosine of the angle between them, then (f_1+f_2) and (f_1-f_2) are the only frequencies obtained. If the coupling does not follow this law, then sidebands corresponding to harmonics of f_2 will also appear in the output of coil S.

Fig. 1b shows a modification of Fig. 1a in which capacitative coupling is used instead of inductive coupling between stator and rotor, and which is 40 more practical for very high frequencies. This arrangement also produces a double-sideband output, like any balanced modulator.

The mechanical construction of this "capacity" or "double condenser" arrangement may take 45 many forms. Fundamentally it is a condenser

with two independent stators S_1 , S_2 , and two rotors R_1 , R_2 which are mechanically coupled to rotate together and each cooperates or "meshes" alternately with the two stators to form a variable condenser therewith. If the two condensers thus formed between rotors and stators at all times are well matched, then no carrier wave will be transmitted therethrough. By shaping of the vanes in known manner, the law of variation of coupling with angular position of the rotors can be made to follow a cosine law, when a simple double-sideband will be produced, (f_1+f_2) and (f_1-f_2) .

If the two pairs of stators of two double-sideband generators are fed by carrier waves of the same frequency but different phase, for example, $e \sin w_1 t$ and $e \sin (w_1 t + \alpha)$ giving the effect of a rotating field, and if the rotors are coupled together mechanically at an angle of α and rotated at a speed of n revolutions per second, $(2\pi n = w_2)$ in the same direction as the rotation of the field, and if the outputs from the rotors are connected in parallel to give a single output, this output equals:

$$e \sin w_1 t \sin w_2 t - e \sin (w_1 t + \alpha) \sin (w_2 t + \alpha) = \frac{e}{2} [\cos (w_1 - w_2)t - \cos (w_1 + w_2)t] -$$

15 15 both of these cases, a transmission line is formed into a loop P having a length equal to m wavelengths of the frequency f_1 carried by the line, and the output is coupled to the line through rotating collector or collectors R , R_1R_2 preferably of the capacity type, i. e. arranged so as to form a capacity with the line as shown. The collectors rotate at frequency f_2 . Since a single revolution

$$20 = \frac{e}{2} [\cos (w_1 - w_2)t - \cos [(w_1 + w_2)t + 2\alpha]]$$

$$= \frac{e}{2} [\cos [(w_1 + w_2)t + 2\alpha] - \cos (w_1 + w_2)t]$$

which expression contains a single frequency

$$\frac{(w_1 + w_2)}{2\pi}$$

Preferably the angle α should be

$$\frac{\pi}{2}$$

and the total output for the case under consideration is then $e \cos (w_1 + w_2)t$. For any other angle, the total output is smaller.

A similar result is obtained if the rotors are rotated in the opposite direction to that of the rotating field effect, giving a frequency

$$\frac{(w_1 - w_2)}{2\pi}$$

It is not necessary, in practice, however, for obtaining a single sideband to use two ganged double-sideband generators. The same principle of operation can be used to provide the single sideband generators as shown diagrammatically in Figs. 2a and 2b, which are respectively in effect the radio goniometer commonly used for radio direction finding purposes (Fig. 2a), and the equivalent capacity goniometer (Fig. 2b). In these goniometers, one field coil F_1 (Fig. 2a), or one pair of stators S_1 , S_2 (Fig. 2b) is fed with a carrier $e \sin w_1 t$, and the other field coil F_2 or pair of stators S_3 , S_4 is fed with a carrier

$$e \sin \left(w_1 t + \frac{\pi}{2} w_2 \right)$$

The field coils or pairs of stators are arranged at right angles to each other and a single rotor revolves at

$$n = \frac{w_2}{2\pi} \text{ revs./sec.}$$

to provide an output at frequency

$$\frac{w_1 + w_2}{2\pi} \text{ or } \frac{w_1 - w_2}{2\pi}$$

according to the sense of rotation.

One suitable method for feeding the di-phase

4 (or polyphase) carrier inputs to the single sideband modulator is by the use of a separate valve amplifier for each input. Two or more modulators may, of course, be operated from the same pair of inputs and a high degree of balance between the outputs from the modulators will still be maintained. Imperfect balance between the valves used to provide polyphase currents will cause imperfect suppression of the unwanted sideband, but this will be of no importance in the application of the modulator to radio beacon systems.

Figs. 3a and 3b show modified forms of the single sideband generator, for respectively unsymmetrical and symmetrical inputs and outputs. In both of these cases, a transmission line is formed into a loop P having a length equal to m wavelengths of the frequency f_1 carried by the line, and the output is coupled to the line through rotating collector or collectors R , R_1R_2 preferably of the capacity type, i. e. arranged so as to form a capacity with the line as shown. The collectors rotate at frequency f_2 . Since a single revolution

35 35 of the collectors adds to or subtracts from the input wave m cycles, the output will be $f_1 + mf_2$, or $f_1 - mf_2$ according to direction of rotation of the collectors.

In practice this system is not workable without special precautions, for the open ended transmission line to which the collectors are capacitatively coupled will produce virtual short-circuits across the line at odd multiples of quarter wavelengths from the open end. This may be avoided by a resistance termination of the line, but such a remedy is rather wasteful with regard to power.

One method for preventing the unwanted effect of the open line is illustrated in Figs. 6a, 6b, and 45 45c. These figures are perspective diagrams of a second or "dummy" collector. In Fig. 6a, the loop P corresponding to the loop P in Fig. 3a, is in one plane together with its rotating collector R for picking up the output. The loop Q is in another plane together with its collector D and the inductance coil I_3 and the ground connection. The loop Q is an open line connected in parallel with the loop P at the point 14. The method is to arrange a second or "dummy" collector D for the case of Fig. 3a or second or "dummy" pair of collectors D_1 , D_2 (see Fig. 6b) for the case of Fig. 3b, which terminate the line in a very low impedance at a point one quarter wavelength nearer to the open end of the line than the output 50 50 collectors R , or R_1R_2 . Fig. 6b is a perspective view of an arrangement of dummy collectors for the type of modulator illustrated in Fig. 3b. The loop P_1 together with the collector R_1 and the associated output conductor lie in one plane. The loop P_2 and its associated collector R_2 and its associated output conductor lie in another plane. The collectors P_1 and P_2 correspond to those illustrated in Fig. 3b. The loop Q_1 and its collector D_1 and the coil I_3 associated with D_1 lie in another 55 55 plane and the loop Q_2 , its associated collector D_2 , and its associated inductance coil I_3 lie in the fourth plane. Q_1 , Q_2 , D_1 and D_2 represent the arrangement disclosed in this paragraph. The loop Q_1 is connected to the loop P_1 at 14 and the loop Q_2 is similarly connected to the loop D_2 .

They are conductors in parallel with the respective loops. In both Figs. 6a and 6b, the dummy collectors D or D₁, D₂ are placed at an angle such that they will effectively terminate the line one quarter of a wave length nearer to the open end of the line than the output collectors R, or R₁, R₂ are. The line between the points 10 and 17 is the projection of the dummy collector D in Fig. 6a and the dummy collector D₁ in Fig. 6b on to the plane of the coil P or P₁. The distance from 9 to 10 measured on the circumference is equal to a quarter of a wave length of the high frequency f_1 . This will have the effect of giving the "dead" end of the transmission line a very high terminating impedance, and no power will be lost. The impedance at the position of the output collectors is always the characteristic impedance of the transmission line. The low impedance or "dummy" collectors are preferably of similar type to the "output collectors," and are arranged virtually to short-circuit the transmission by terminating them with an inductance 13 which tunes out the capacity of the collector coupling. This "dummy" collector must not of course short circuit the input transmission line when the output collector is on the last quarter-wavelength portion of the line loop. In practice, the "dummy" collectors are arranged to rotate around conductors Q or Q₁, Q₂ in parallel with the loop conductors P or P₁, P₂, and the portion of the parallel conductors 11, representing the first portion of the loops covered by the collectors are omitted. Conductor loops Q or Q₁, Q₂ are connected to the loops P or P₁, P₂ at the points 14. These points are one quarter of a wave length distance from the points 15 at which the line is attached to the conductor loops P or P₁, P₂. To operate correctly it is necessary that the distance 14 to 16 is negligible with respect to a quarter wave length or that it is a full wave length.

When the modulation frequencies required are too high for rotation of collectors at the fundamental, a transmission line loop of several wavelengths may be used. If the total size becomes too large, it is not necessary to collect output from all points of the line as the latter may be looped out of the circle, returning to suitable electrodes E₁, etc. at intervals of quarter-wavelengths as is shown in Fig. 4 for an unsymmetrical system. In this case correct matching of the output is maintained if a very low impedance auxiliary or "dummy" collector D (see Fig. 6c) is arranged to rotate with the output collectors but always one electrode, i. e. one quarter-wavelength of transmission line nearer to the open end, i. e. electrode No. 8. As illustrated in Fig. 6c the dummy collector D is at the electrode 20 which corresponds to electrode 4 in distance from the open end of the transmission line whereas the output collector is at electrode 3. Electrode 3 is one quarter of a wave length further from the open end of the transmission line. As in the previous case described this "dummy" collector must not short-circuit the input line in position of electrode No. 1 when the output collector is on the last electrode: in practice it is arranged to rotate round a set of parallel electrodes 18, 19, 20, 21, 22, 23 and 24 in which set the first electrode is omitted, i. e. the electrode that would correspond to electrode 1 in distance from the open end of the transmission line is omitted. Connection is made between the loop P and the loop Q from the electrode 2. The loop Q and its dummy collector D lie in a different plane from that in which the loop P lies and to make this obvious

the loop Q has been drawn in a broken line although it is a real part of the circuit. In this arrangement as in the previous one described the "dummy" collectors are arranged to short circuit vertically the transmission by terminating them with an inductance which tunes out the capacity of the collector coupling.

Still another modification is shown on Fig. 5 for an unsymmetrical system in which two carrier inputs from L₁, L₂ are used and, are of the same frequency f_1 , but in phase quadrature. The lines L₁, L₂ from each source contact with alternate electrodes E₁, etc. The electrodes of each set E₁—3—5 etc. or E₂—4—6 etc. are connected either by very short leads, or by leads of half wavelengths. In the arrangement shown in Fig. 5 "dummy" or short-circuiting collectors are required and arranged as described in connection with Figs. 6a, and 6c, and the sideband frequency produced corresponds to double the speed of rotation of the collector. It will be observed that the electrical distance between two successive electrodes is virtually one quarter-wavelength.

It will be understood from the examples described that many variations of the single sideband generator are possible without departing from the scope of the invention. The essential principle is the rotation of mechanical parts at the frequency of the required sideband or at a sub-multiple of the required frequency when a polyphase current is employed.

The single sideband generators are particularly applicable to and provide a simplification in radio landing systems. For example, if a carrier wave of frequency f_1 is radiated omnidirectionally in the horizontal plane, but with high horizontal directivity in a vertical plane, and if sidebands f_2 and f_3 are radiated on aerials of different directivity in the horizontal plane, then a receiver tuned to the total transmission will have three frequencies f_1-f_2 , f_2-f_3 , f_3-f_1 , in its output. Any particular predetermined relative values of the amplitudes of these three frequencies defines a definite line in space.

What is claimed is:

1. A modulator for the production of a single side band corresponding to the modulation product of a high frequency wave modulated by a low frequency and for the elimination of the carrier wave, comprising a source of high frequency voltage, a first transmission line, a first conductor that is one of the pair of conductors of said first transmission line and is formed into an open loop whose circumferential length is an integral number of wave lengths of said high frequency, means for applying voltage from said source to said first conductor, a second transmission line, a second conductor that is one of the pair of conductors of said second transmission line, means for capacitatively coupling said second conductor to said first conductor, means controlled by the low frequency to rotate said second conductor around said loop so that the frequency of the high frequency voltage transferred by the capacitative coupling to the said second conductor is either greater than or less than the said high frequency by an amount equal to the said low frequency.
2. A modulator according to claim 1 in which the first transmission line is a symmetrical line, the other conductor of the said first transmission line is formed into an open loop whose circumferential length is an integral number of wave lengths of the high frequency, and a rotating

conductor is capacitatively coupled thereto to form a symmetrical output.

3. A modulator according to claim 1 in which the source of high frequency voltage comprises a source of polyphase current of said high frequency, the first conductor comprises a plurality of conductors each of which carries one phase of said polyphase current and each of which is formed into an open circular loop whose circumferential length is an integral number of wave lengths of said high frequency, the means for coupling said second conductor comprises means coupling it to each of the said plurality of conductors.

4. A modulator according to claim 1 in which the first conductor is subdivided into a plurality of equal lengths of a fraction of a wave length of the high frequency, plates are arranged around the circumference of a circle, the ends of the said lengths are connected electrically to said plates, the means for capacitatively coupling said second conductor to said first conductor comprises means capacitatively to couple cyclically and in succession to said plates.

5. A modulator according to claim 1 in which the source of high frequency voltage comprises a source of polyphase current of said high frequency, plates are arranged around the circumference of a circle, the first conductor comprises a plurality of conductors, said conductors each carrying one phase of said polyphase current and each being subdivided into a plurality of equal lengths of a fraction of a wave length of the high frequency, the ends of said equal lengths are connected electrically to the said plates, the corresponding plates of the respective phases are placed in succession around said circle, and the means for capacitatively coupling said second conductor to said first conductor comprises means capacitatively to couple cyclically and in succession to said plates.

6. A modulator according to claim 1 further comprising an auxiliary conductor, means 20 couple capacitatively said auxiliary conductor to the first conductor, said means being arranged 45 one-quarter of a wave length nearer to the open end of said loop than the second conductor, and means associated with said auxiliary conductor to render it an effective short circuit for the first transmission line.

7. A modulator according to claim 1 further comprising an auxiliary conductor, means capacitatively to couple said auxiliary conductor to the first conductor, said means being arranged one-

quarter of a wave length nearer to the open end of said loop than the second conductor, means to break the coupling of said auxiliary conductor to said first conductor when the said second conductor is coupled to the loop at a point within the last quarter wavelength of the loop, and means associated with said auxiliary conductor to render it an effective short circuit for the first transmission line.

8. A modulator comprising first and second transmission lines, a first frequency energy source for energizing said first line, means for coupling a portion of said second line to said first line and means for cyclicly varying the point of said coupling along an integral number of wave lengths at said first frequency of said first line.

9. An arrangement according to claim 8 wherein said coupling means comprises capacitive coupling of a portion of the said second line to said first line.

10. An arrangement according to claim 9 wherein said portion is moved along an integral number of wave lengths at said first frequency of said second line at a given repetition rate and in continuous capacitive coupling therewith.

11. An arrangement according to claim 8 wherein a portion of said second line is capacitively coupled to consecutive spaced portions of said first line over an integral number of wave lengths thereof at said first frequency and at a given repetition rate.

12. An arrangement according to claim 11 wherein said spaced portions are spaced a quarter wavelength at said first frequency.
